UNITED STATES PATENT OFFICE.

WALLACE E. MEYERS, OF NEW YORK, N. Y., ASSIGNOR TO LOUIS MEYERS & SON, INC.,
OF NEW YORK, N. Y., A CORPORATION OF NEW YORK.

DESIGN FOR A GLOVE OR THE LIKE.

Application filed March 21, 1929. Serial No. 30,572. Term of patent 7 years.

To all whom it may concern:

Be it known that I, WALLACE E. MEYERS, a citizen of the United States, and a resident of the city of New York, borough of Manhattan, in the county of New York, and State of New York, have invented the new, original, and ornamental Design for Gloves or the like, of which the following is a specification.

Reference is to be had to the accompanying drawings—

I claim:

The ornamental design for a glove or the like, as shown.

Signed at New York in the county of New York and State of New York this 19th day of March A. D. 1929.

WALLACE E. MEYERS.
